ABSTRACT

A motor-barrel watch movement in which the barrel arbor is cylindrical with longitudinal grooves one of which acts as the spring anchor. There are four bearing regions for supporting the pivoting of the arbor in the frame and the pivoting of the barrel on the arbor.

PATENTED NOV 12 1974

3,846,974

FIG. 1

FIG. 2

MOTOR-BARREL WATCH MOVEMENT

SUMMARY OF THE INVENTION

Essentially the object of the present invention is to achieve a reduction in manufacturing costs of motor-barrel watch-movements by simplifying the barrel arbor and the motor assembly.

In most watch movements, the barrel arbor will be a profile-turned part with six to eight shoulders of different diameters along its length. Furthermore, the central part, which is of maximum diameter, is provided with several millings forming a hook to which is fastened the inside end of a spring-motor also equipped with a hook formed by bending the spring at a right angle. Of those shoulders of different diameters, four are used for pivoting and consequently must be machine finished. It will be clear that under such conditions, the manufacture of these barrel arbors consists of a sequence of costly operations.

Cylindrically shaped barrel arbors already are known, which are detachably mounted in the movement frame. However, as regards these known devices, an additional piece acting as core, that is, as the central component of the arbor, and ensuring that the spring-motor is hooked, will be placed inside the drum. This additional piece is provided with a cylindrical passage in the direction of its axis, and the cylindrical arbor will be placed inside said passage. Also, the core must be machined together with its hook. Further, the detachable arbor is provided with a pivoting shoulder which must be machined on the lathe. While such a known device facilitates barrel disassembly, it does nothing to simplify the manufacture of the arbor and will not lower its manufacturing cost.

Cover-less barrels provided with an elongated hub and mounted on a long cylindrical shoulder are also known. However, as regards these known devices, the core again is a separate piece which must be mounted on the arbor where it will form a separate collar surrounding the hub of the drum, whereby arbor machining is considerably hampered.

Lastly, barrel arbors are known, wherein the core hook is replaced by a groove running parallel to the barrel arbor and fashioned into its central shoulder. In these devices again, many manufacturing operations are required to achieve the arbor.

In order to reduce the number of operations involved in the manufacture of a barrel arbor and to facilitate assembly of the motor-sets for watches, the object of the present invention is a motor-barrel watch-movement characterized in that the barrel arbor is made of one piece provided with anchoring means for the spring-motor and with a circular surface the pivoting of the arbor in the movement frame and pivoting of the barrel about the arbor is oriented by four annular components bearing on said cylindrical surface of said arbor. These annular components extend to the level of the apertures made on one hand in two components of the frame and on the other hand in the drum and in the barrel cover.

The attached drawing illustrates two embodiments of the watch-movement of the invention.

FIG. 1 is a fragmentary view in cross-section of one of those embodiments taken in a plane containing the barrel axis; and

FIG. 2 is a fragmentary view in cross-section of the other of those embodiments also taken in a plane containing the barrel axis.

As will be observed from the present description, the two embodiments shown in the drawing may be executed as different variations of the barrel arbor. The first embodiment relates to a watch-movement in which the ratchet-wheel 2 is mounted on the arbor of barrel 1 and lies between the drum of barrel 3 and the bridge of barrel 4. A cover 14 is fastened to the drum of barrel 3, these two components being bored by central apertures 5 and 6 of the same diameter. Further, aperture 7, which is fashioned in bridge 4 in order to ensure rotation of the upper end of arbor 1, and aperture 8, which is fashioned in the bottom plate 9 to ensure the rotation of the lower end of arbor 1, are of the same diameter as apertures 5 and 6, however, aperture 8 being partly closed towards the outer side of the bottom plate by an annular flange 10 which was made during machining and which provides an axial stop for arbor 1.

Arbor 1 is made of a simple piece and is mainly characterized by cylindrical lateral surface of constant diameter along the entire length except at the lower end, which is provided with a frustoconical bevel 11. Lateral surface 15 is sectioned by four longitudinal grooves 16 at 90° to each other and extending over the entire length of arbor 1. These grooves are rectangular in cross-section, but may also be of any other shape if necessary. It is, therefore, one and the same cylindrical surface which ensures rotation of the arbor with respect to the frame in apertures 7 and 8 and rotation of the barrel about the arbor, by means of apertures 5 and 6. The spring-motor 17, therefore, will be provided with a hook at its lower end for entering one of grooves 16.

Arbor 1 may be manufactured in such manner that the cost will be particularly low. Starting with calibrated cylindrical bars drawn with four grooves 16, it will suffice to section these bars on an automatic lathe and to machine the bevel 11 in order to obtain the arbor blanks. The latter may be tumble-polished, which provides a particularly simple and effective method for that purpose. Grooves 16 also may be milled, but it is more efficient to draw them. It will be to advantage to foresee several grooves for easier assembly. Once the arbor has been made, the ratchet-wheel 2 will be force-fitted on its outer wall, the central aperture of said ratchet-wheel being provided with two or as many as four catches 18 adapted to the dimensions of grooves 16. This assembly will rigidly connect wheel 2 with arbor 1.

It is apparent that ratchet-wheel 2 will engage the movement's crown-wheel which is located inside bridge 4.

As regards assembly, spring 17 will be so wound that its last coil will be of a lesser diameter than that of arbor 1. This spring being housed in barrel 3, 14, the frustoconical bevel 11 of arbor 1 penetrates the last coil of the spring and the arbor is placed into the center of the spring to the desired height, the spring's hook entering one of grooves 16. Ratchet-wheel 2 having previously been force-fitted and set with respect to height, barrel assembly, therefore, will take place conventionally. The spring alone ensures keeping the barrel at the proper height. It will be observed that the width of the grooves is about three times the thickness of the spring. Their angles will be rounded off and polished during

the tumble-polishing stage, so that the presence of these grooves in the various regions of the bearing-blocks will not cause premature wear of latter.

In order to set the arbor with respect to height, one must precisely observe the tolerances of dimension *a* between the lower end of arbor 1 and the location of the upper side of ratchet-wheel 2. When in operation, the positioning of the arbor with respect to height is determined on one hand by the flange 10 supporting the lower end of arbor 1, and on the other by the boss 19 in bridge 4 near aperture 7, said boss stopping the upper side of wheel 2. Dimension *d* corresponds to the axial play of the arbor, which may be adjusted by force-fitting wheel 2 to the desired height *a*. Dimension *c* between barrel cover and the inside of the bottom plate must be larger than zero. Such an arrangement provides a particularly simple manufacture of the barrel arbor.

The embodiment of FIG. 2 shows an arbor the same as arbor 1, but of somewhat different location with respect to the frame components. In this latter embodiment, the ratchet-wheel 20 is fastened as above to the upper end of arbor 1. The latter's circular surface traverses aperture 21 in barrel bridge 22 from top to bottom, then passes through aperture 23 of barrel 24, then aperture 25 of cover of barrel 26, and then aperture 27 of bottom plate 28. Spring motor 17 is fastened by its lower end to arbor 1 in the same manner as in FIG. 1.

In order to ensure that arbor 1 and wheel 20 be kept in a proper axial position, the crown-wheel 29 is provided with teeth of which the edges 29a are slightly sloped with respect to the plane of the wheel. The teeth of wheel 20 are similarly inclined. Crown-wheel 29 is maintained in the axial position by a screw, as in conventional watch movements, so that the edges 29a lock wheel 20 and arbor 1 in the axial sense in such manner that there will be no play between wheel 20 and gear-train bridge 22. A support plate provided with pins 30 passing through apertures fashioned in bottom plate 28 and supporting the barrel in the proper height and resting against its cover is used for assembly. This support may comprise several pins 30.

This embodiment may be varied by providing the barrel arbor with a machined square at its upper end and with a threaded bore at the axis. In such case, the ratchet-wheel also would be provided with a square aperture, —as in conventional circumstances—, and would be fastened to the arbor's square by a screw of which the head's diameter would be approximately the same as the square's diagonal. Such an arrangement also would allow to finish the rotational surfaces by tumble-polishing, which is more effective than rolling.

Another advantage will be obtained from this second embodiment and the variation that have just been described: the barrel arbor and the ratchet-wheel may be easily removed from the frame, as if of one piece. The far hook of spring 17 will be removed the moment the arbor has been pulled axially over a sufficient length. One may then withdraw the motor-barrel from the movement, provided the components fastened between the barrel bridge and the bottom plate are arranged to leave free passage to the barrel between the barrel and the periphery of the movement. In lieu of being provided with catches at its central aperture, ratchet-wheel 20 might also be provided with a circular aperture ad-

justed to the diameter of piece 1 and force-fitted to same.

The embodiments and the variation thereof just described provide the following advantages:

One may manufacture arbors 1 from bars with grooves formed therein during drawing thanks to a drawing die of suitable shape.

Because of the cylindrical lateral surface stretching over its entire length, arbor 1 meets very stringent requirements. It was observed that the initial bars could be trued by means of grinders working on a roller-mounted bar (CENTERLESS process), which fact considerably simplifies the manufacture and allows achieving high accuracy.

Machining on automatic lathes for bars is extremely simple.

The feasibility of tumble-polishing large quantities of arbors also constitutes simplification in manufacture.

Lastly, as previously mentioned, the described arrangement facilitates assembly and disassembly of the barrel.

In the case of a self-winding watch movement, the pinion(s) meshing with the ratchet-wheel 6 may be pinions of the self-winding mechanism. They may also be provided with slanting toothing.

As explained above, the use of cylindrical bars extruded through a contoured die for four longitudinal grooves allows particularly efficient manufacture of barrel arbors. However, hooking the spring-motor in a longitudinal groove of the arbor is not the sole economical solution to the problem in question. Fastening the spring to the arbor also may be achieved by fashioning an aperture or a cut-out in the end of the spring and winding latter around itself on the arbor. The spring then is connected to the arbor by clamping. In this case, arbor manufacture is particularly advantageous with respect to cost, since one needs only a cylindrical bar which will be sectioned.

What is claimed is:

1. A motor-barrel watch movement characterized in that the barrel arbor is made of one piece with a circular, cylindrical surface, and in which rotation of the arbor in the frame of the movement and the rotation of the barrel about the arbor are ensured by four annular bearings surrounding said cylindrical surface and which lie in the space between an aperture fashioned on one hand in two of the frame components and on the other, in the drum and the barrel cover, said arbor including an anchoring means for the spring motor characterized as a recess formed in the cylindrical surface of said arbor.

2. A movement as defined in claim 1, in which the barrel arbor is square at one end, and further comprising a ratchet-wheel having a square central aperture fastened to said square end of said arbor.

3. A motor barrel watch movement having a barrel arbor and spring motor characterized in that the barrel arbor is made of one piece with a circular cylindrical surface and in which rotation of the arbor in the frame of the movement and the rotation of the barrel about the arbor are ensured by four annular bearings surrounding said cylindrical surface and which lie in the space between an aperture fashioned on one hand in two of the frame components and on the other in the drum and the barrel cover wherein said cylindrical surface of said arbor is provided with at least one longitudinal groove anchoring the inner end of the spring mo-

tor, and thus constituting the anchoring means therefor.

4. A movement as defined in claim 3, characterized in that said barrel arbor is provided with four longitudinal grooves at 90° from one another.

5. A movement as defined in claim 3, further comprising a ratchet-wheel provided with a central profiled aperture with at least one catch capable of entering said groove, said ratchet-wheel being force-fitted on said arbor with said catch in said groove.

6. A motor barrel watch movement having a barrel arbor and spring motor characterized in that the barrel arbor is made of one piece with a circular cylindrical surface and in which rotation of the arbor in the frame of the movement and the rotation of the barrel about the arbor are ensured by four annular bearings surrounding said cylindrical surface and which lie in the space between an aperture fashioned on one hand in two of the frame components and on the other in the drum and the barrel cover wherein the arbor mounting aperture of one of the frame components is provided with an inner shoulder in the vicinity of its outer surface, this shoulder acting as an axial step for the barrel arbor.

7. A movement as defined in claim 6, characterized in that said cylindrical surface of said arbor is provided with at least one longitudinal groove, and further comprising a ratchet-wheel surrounding said arbor and hav-

ing a catch in said groove, said ratchet-wheel being adjusted in height on the arbor in such manner that it will lie between the barrel and the frame component ensuring rotation of the arbor's other end, the height adjustment of the ratchet-wheel being such that this wheel together with the inner surface of said frame component limits the axial play of the arbor.

8. A motor barrel watch movement having a barrel arbor and spring motor characterized in that the barrel arbor is made of one piece with a circular cylindrical surface and in which rotation of the arbor in the frame of the movement and the rotation of the barrel about the arbor are ensured by four annular bearings surrounding said cylindrical surface and which lie in the space between an aperture fashioned on one hand in two of the frame components and on the other in the drum and the barrel cover wherein the ratchet wheel is fastened to one end of the arbor and extends outside the frame and in that the axial positioning of the arbor is ensured on one hand by a stop rigidly connected to the frame and operating in concert with the ratchet-wheel and on the other by an oblique toothed of a wheel-and-pinion mounted on the frame and meshing with the ratchet wheel.

9. A movement as defined in claim 8, characterized in that said wheel-and-pinion is the crown-wheel.
